L. OVERBAUGH

SPRINKLER NOZZLE

Filed April 5, 1922

INVENTOR.
LESLIE OVERBAUGH.

BY *A. B. Bowman*
ATTORNEY

UNITED STATES PATENT OFFICE.

LESLIE OVERBAUGH, OF SAN DIEGO, CALIFORNIA.

SPRINKLER NOZZLE.

Application filed April 5, 1922. Serial No. 549,755.

To all whom it may concern:

Be it known that I, LESLIE OVERBAUGH, a citizen of the United States, residing at San Diego, in the county of San Diego and State 5 of California, have invented certain new and useful Sprinkler Nozzles, of which the following is a specification.

My invention relates to sprinkler nozzles, more particularly to nozzles of this class for 10 lawn sprinkling purposes and the objects of my invention are: first, to provide a device of this class which is particularly adapted for sprinkling a spray of water into passage ways or corners, or sprinkling outwardly 15 from said places; second, to provide a device of this class which can be adjusted to discharge water in various quantities, directions and in various widths of sprays; third, to provide a device of this class which can 20 be readily adjusted to produce sprays of varying fineness as desired; fourth, to provide a novelly constructed sprinkler nozzle, and fifth, to provide a device of this class which is very simple and economical of construction, durable, easily adjusted and installed and which will not readily deteriorate or get out of order.

With these and other objects in view as 30 will appear hereinafter my invention consists of certain novel features of construction, combination and arrangement of parts and portions as will be hereinafter described in detail and particularly set forth in the appended claims reference being had to the 35 accompanying drawings and to the characters of reference thereon which form a part of this application in which:

Figure 1 is a side elevational view of my 40 device secured to a water main buried beneath the lawn and shown partly in section to facilitate the illustration; Fig. 2 is a sectional view through the center of the sprinkler head of my device and Fig. 3 is a plan view of my device partly in section to facilitate the illustration showing by dotted lines 45 various positions of the sprinkler adjusting member and also showing by dotted lines the respective widths or sectors of the sprays caused by the various positions of said sprinkler adjusting member.

Like characters of reference refer to similar parts and portions throughout the several views of the drawings.

The sprinkler head 1, the sprinkler adjusting member 2, and the washer 3 consti-

tute the principal parts and portions of my device.

The sprinkler head 1 is provided with a central threaded hole 1^a in one end thereof adapted to receive the pipe nipple A connected to and communicating with a water main, and is also provided with a reduced threaded hole 1^b concentric with the former extending the remaining distance therethrough and adapted to receive the sprinkler 60 adjusting member 2. Said sprinkler head 1 is further provided with a semi-circular bevelled edge 1^c extending outwardly from the hole 1^b in a semi-cone shaped manner. The sprinkler adjusting member is cylindrical in 65 shape and provided with external threads 2^a adapted to engage the threads 1^b of the sprinkler head 1 as described above and is also provided with a concentric hole 2^b extending therein from the inner end thereof. 70 A narrow diagonal slot 2^c is provided near the upper end of said sprinkler adjusting member communicating with the small central hole 2^b therein and with the exterior 75 thereof substantially in line with the bevelled edge 1^c of the sprinkler head 1. Said member 2 is further provided with a transverse slot 2^d at one end thereof adapted to be 80 engaged by a screw driver for adjusting the same with respect to head 1. A gasket 85 washer 3 is interposed between the shoulder 1^a within the member 1 and the free end of the nipple A to insure a water-tight joint and further, to provide a means for frictionally engaging the adjusting member 2 90 and retaining the same in the various adjusted positions.

Though I have shown and described a particular construction, combination and arrangement of parts and portions I do not 95 wish to be limited to this particular construction, combination and arrangement but desire to include in the scope of my invention the construction, combination and arrangement substantially as set forth in the 100 appended claims.

It is obvious that the spray of water issuing from the nozzle is directly proportional to the longitudinal adjustment of the adjusting member 2 with respect to the head 1 105 and also that the angular position of the member 2 with respect to the head 1 governs the width and the general direction of the spray issuing therefrom, as shown by dotted lines in Fig. 3 of the drawings.

Having thus described my invention what I claim as new and desire to secure by Letters Patent is:

1. In a sprinkler nozzle, the combination 5 with a supply line, of a sprinkler head provided with a threaded hole adapted to receive the threaded end of said supply line and another threaded hole concentric with the former, and a sprinkler adjusting member 10 adjustably secured in said last named threaded hole of said sprinkler head, provided with a central hole extending therein from the inner end thereof and communicating with the exterior upper portion of 15 said adjusting member by a narrow diagonal slot terminating at the upper edge of the sprinkler head and substantially in line with said edge.

2. In a sprinkler nozzle, the combination 20 with a supply line, of a sprinkler head provided with a threaded hole adapted to receive the threaded end of said supply line and another threaded hole concentric with the former, a sprinkler adjusting member adjustably secured in said last named threaded 25 hole of said sprinkler head, provided with a central hole extending therein from the inner end thereof and communicating with the exterior upper portion of said adjusting 30 member by a narrow diagonal slot terminating at the upper edge of the sprinkler head and substantially in line with said edge, and a gasket washer secured in the larger threaded hole of said sprinkler head against 35 the shoulder provided therein by the different sized holes, adapted to frictionally engage the inner portion of said sprinkler adjusting member.

3. In a device of the class described, the 40 combination with a supply line, of a sprinkler head provided with concentric threaded holes adapted to receive in one of said holes

the external threaded end of the said supply line and further provided with a bevelled inner edge at the free portion thereof in an 45 inverted substantially semi-conical shaped manner, a sprinkler adjusting member secured in the other of said threaded holes in said sprinkler head, provided with a central hole extending therein from the inner portion thereof and with a diagonal slot communicating with said central hole substantially in line with the bevelled edge of said 50 sprinkler head and a means in connection with said sprinkler adjusting member for 55 adjusting the same with respect to said sprinkler head.

4. In a device of the class described, the combination with a supply line, of a sprinkler head provided with concentric threaded 60 holes adapted to receive in one of said holes the external threaded end of the said supply line and further provided with a bevelled inner edge at the free portion thereof in an 65 inverted substantially semi-conical shaped manner, a sprinkler adjusting member secured in the other of said threaded holes in said sprinkler head, provided with a central hole extending therein from the inner portion thereof and with a diagonal slot communicating with said central hole substantially 70 in line with the bevelled edge of said sprinkler head, a means in connection with said 75 sprinkler adjusting member for adjusting the same with respect to said sprinkler head, and a means adapted to frictionally engage the said sprinkler adjusting member for retaining said member in various adjusted positions with said sprinkler head.

In testimony whereof, I have hereunto set my hand at San Diego, California this 30th day of March, 1922.

LESLIE OVERBAUGH.
